DESIGN FOR A PLAQUETTE

Louis Detkin and Samuel H. Berg, Brooklyn, N. Y.

Application April 9, 1942, Serial No. 106,513

Term of patent 3½ years

To all whom it may concern:

Be it known that we, Louis Detkin and Samuel H. Berg, respectively citizens of the United States and residents of the Borough of Brooklyn, county of Kings, city and State of New York, each with a post office address at No. 36 West 32nd Street, New York city, have invented a new, original, and ornamental Design for a Plaque, of which the following is a specification, reference being had to the accompanying drawing, forming part thereof, in which:

We claim:

The ornamental design for a plaque, as shown.

LOUIS DETKIN.

SAMUEL H. BERG.
